(57) **CLAIM**

The ornamental design for a beverage container, as shown and described.

DESCRIPTION

FIG. 1 is a front view of a beverage container showing my new design; the rear view being a mirror image thereof; FIG. 2 is a top view thereof; FIG. 3 is a bottom view thereof; and, FIG. 4 is a perspective view thereof.

The back view is omitted because this view is a mirror image of the front view.

The broken lines in the drawings depict portions of the beverage container that form no part of the claimed design.
